UNITED STATES PATENT OFFICE.

ERASTUS E. WINKLEY, OF LYNN, MASSACHUSETTS.

DETONATING MECHANISM.

Application filed January 21, 1914. Serial No. 912,104.

To all whom it may concern:

Be it known that I, ERASTUS E. WINKLEY, a citizen of the United States, residing at Lynn, in the county of Essex and State of Massachusetts, have invented certain new and useful Improvements in Detonating Mechanism; and I do hereby declare the following to be a full, clear, and exact description of the invention, such as will enable others skilled in the art to which it pertains to make and use the same.

The present invention relates to a detonating mechanism such as may be employed in vehicles for carrying explosives which are to be detonated when the vehicles have reached a predetermined place, or have been in travel for a predetermined length of time.

The object of the invention is to produce a positively acting detonating mechanism of such simple construction that it may be manufactured cheaply and in a form adapting it for application and ready attachment to any kind of vehicle, whether aerial, marine, or terrestrial, which may be employed for carrying an explosive to a desired point at which the explosive is to be detonated in order to effect the destruction or annihilation of any object natural or artificial. To the accomplishment of this object and such other objects as are incidental thereto which shall hereinafter appear, the invention resides in the structure particularly pointed out in the claims, a specific form of this structure being described in the following specification.

The preferred form in which it is contemplated embodying the invention is illustrated in the accompanying drawings, in which Figure 1 is a sectional side elevation taken on the line 1—1 of Fig. 2; Fig. 2 is a sectional plan taken on the line 2—2 of Fig. 1; Fig. 3 is a view similar to Fig. 1, showing the positions of the parts of the detonating mechanism when the percussion means thereof is cocked ready to effect a detonation of the explosive when the vehicle carrying the explosive has reached its destination; and Fig. 4 is a similar view showing the parts of the detonating mechanism at the instant of detonating the explosive.

In the illustrated embodiment of the invention the detonating mechanism is shown as enclosed in a casing 5. The mechanism may thus be handled in convenient form so as to be readily applicable to any type of vehicle which may be employed for the pur-

pose of carrying the explosive to the point where it is to be detonated. Assuming that the vehicle travels at a given rate of speed, it will, barring accidents, reach its destination in a definite period of time. The lapse of this time may be determined by a clock or similar mechanism, or it may be determined by the consumption of the fuel for the propelling means of the vehicle. The form in which the detonating mechanism is embodied is, if for use with end control, by either kind of time measuring means. It is assumed for the sake of convenience, however, that the operations of the mechanism are controlled by the vehicle propelling means. To this end the mechanism is provided with a main shaft 6 which is adapted to be connected with and to be driven by the vehicle propelling means. The construction of the connection between the shaft 6 and the percussion means or means for causing the detonation of the explosive, is such that when the shaft 6 ceases to rotate on the cessation of the operation of the propelling means, the percussion means will not to cause a detonation of the explosive. The shaft 6, of which the part 7 extends outwardly beyond the casing 5 for connection with the vehicle propelling means, extends longitudinally of the casing and is journaled in bosses 8 which project inwardly from the ends of the casing. Collars 9 are provided for the purpose of holding the shaft in operative position.

The percussion means comprises a percussion hammer which is in the form of a lever 10, and a percussion rod 12. The percussion rod 12, which in reality is a part of the percussion hammer, is slidably received in a vertical bore in an elongated boss 11 which depends from the cover 13 of the casing 5. The upper end of the percussion rod 12 is adapted to be forced against the percussion fuse connected with the explosive, when the vehicle reaches the place where the explosive is to be detonated. The lower end of the percussion rod 12 rests lightly on the free outer end of the percussion hammer or lever 10, which is pivoted on a stud 16 fixed in bosses 17 projecting inwardly from the sides of the casing. When the main shaft 6 is not rotating, as shown in Fig. 1, the percussion hammer 10 is not cocked, that is to say, it is not under pressure to force the percussion rod 12 against the percussion fuse of the explosive. When,

however, the shaft 6 has been in rotation for a predetermined length of time, which will be the case when the vehicle carrying the explosive has been in progression for a certain length of time, the percussion hammer 10 will be cocked or under pressure. The means for placing the percussion hammer 10 under pressure consists of a spring 20, the upper end of which encircles a lug 21 depending from a lug 22 extending laterally from the hammer, the lower end of the spring 20 encircling a lug 24 on the end of an arm 25 of a bellcrank lever pivoted on a stud 26 fixed in bosses 27 extending upwardly from the bottom of the casing. The other arm 28 of this bellcrank lever, which may be termed the cocking lever, extends upwardly and is provided with a projection 29 which is normally in the path of motion of the outer end 30 of an arm 31 fixed on a cross-shaft 32 journaled in inwardly extending bosses 33. When the shaft 32 is rotated, the arm 31 swings in the direction of the arrow, as shown in Fig. 1, and its outer end 30 is thereby brought into engagement with the projection 29 on the arm 28, swinging the latter clockwise until its upper end is forced under the barb 34 of a hook 35 loosely mounted on the stud 16. The hook 35 is in unstable equilibrium, and its barb 34 is normally held in the position shown in Fig. 1, by the engagement of a stop 36 on the hook 35 with the adjacent inner side of the end 18 of the casing. When the arm 28 of the cocking lever has been forced under the barb 34 of the hook 35, as shown in Fig. 3, by the rotation of the arm 31, it is thereafter held in that position. If the destination of the vehicle carrying the explosive is at such a distance that the arm 31, which rotates constantly while the main shaft 6 rotates, performs several revolutions, its end 30 will strike the projection 29 as it passes by the latter, but this will have no effect either in causing an actuation of the percussion means or in disengaging the arm 28 from the hook 35.

The cross-shaft 32 is provided with a pinion 38 which is adapted to be engaged by a worm 39 fixed on a jack shaft 40 that is journaled in a long, horizontally disposed bearing 41 projecting from the upper end of a bracket 42, the lower end of which is bifurcated so as to form the arms 43 and 44 which loosely embrace the countershaft 45 journaled in bosses 46 which project inwardly from the sides of the casing. Fixed on the inner end of the jack shaft 40 is a gear 47 which meshes with a worm 48 fixed on the countershaft 45. The outer end of the jack shaft 40 is supported in a fixture 50 which is clamped against the end 18 of the casing by means of a thumb-screw 51 that passes through a vertically elongated slot in the end 18 of the casing. This man-

ner of mounting the jack shaft 40 is for the purpose of permitting the worm 39 to be disconnected from the pinion 38 in order that the arm 31 may be set in any desired position with relation to the arm 28. The nearer to the arm 28 the arm 31 is set, when the vehicle is put in motion, the sooner of course the arm 28 will be engaged by the hook 35 and the sooner the percussion hammer will be thereby cocked or put under pressure. In order to insure safety for those sending the vehicle of destruction on its journey, the arm 31 will be set at such a distance from the arm 28 that the vehicle will be well on its way before the arm 31 contacts with the arm 28 and cocks the percussion hammer. The worm 39 is disengaged from the pinion 38 by loosening the thumb nut 51 and raising the outer end of the jack shaft 40. When the arm 31 is set in the required position, the outer end of the jack shaft is lowered to bring the worm 39 into mesh with the pinion 38, and the thumb nut 51 is tightened to clamp the fixture 50 against the casing. The countershaft 45 is provided with a gear 53 which meshes with a worm 54 secured to the main shaft 6. At this point it will be observed that by reason of the construction of the casing in which the detonating mechanism is enclosed, the countershaft 45, the cross-shaft 32, and the pivot pins or studs 26 and 16 must be inserted through the sides of the casing from the outside, and that, therefore, the parts carried by them are supported within the casing until these cross members are inserted through their hubs.

When the percussion hammer or lever 10 has been cocked or placed under pressure, it is held in that condition while the vehicle carrying the explosive is in progression. For this purpose a centrifugal device is provided, the operation of which is dependent upon the rotation of the main shaft 6. While the main shaft is rotating, the centrifugal device, which is indicated generally by the reference character 55, moves a member into engagement with the percussion hammer and holds it cocked; but when the vehicle carrying the explosive has reached its destination or has been in travel for a predetermined length of time, and the propelling means ceases to operate, so that the main shaft 6 likewise ceases to rotate, the centrifugal device 55 is disconnected from the percussion hammer, and the latter is thereby permitted to strike the percussion fuse of the explosive. The centrifugal device consists of two weights 56 and 57, which are fastened on the outer ends respectively of obliquely disposed rods 59 which are pivoted on a pin 60 passed through a block 62 fastened by the pin 60 to the main shaft 6. A horizontally disposed link 63 is connected at 64 with the obliquely disposed rods 59.

59, and at 65 with a block 66 adjustably secured to a sleeve 67 slidably mounted on the main shaft 6. The end 68 of the sleeve 67 takes against a large flange 69 carried 5 by a second sleeve 70, also slidably mounted on the main shaft. The upper side of the flange 69 is adapted to engage with a horizontally disposed plate 72 secured to the lower end of the boss 14. The flange 69 is thereby prevented from rotating. A spring 73 which loosely embraces the main shaft 6, is interposed between one end of the sleeve 70 and a bracket 75 which serves to support the middle of the shaft 6 and 10 thereby prevent it from buckling. The action of the spring 73 is such that it tends to move the sleeve 70 to the left, viewing Fig. 1, and force the flange 69 away from the outer end of the percussion hammer or 15 lever 10. The leftward movement of the sleeve 70 under the action of the spring 73, carries with it the sleeve 67, so that the link 63 is moved in a direction to force the weights 56 and 57 toward the main shaft. 20 When the main shaft is rotating the the requisite speed, the weights will of course be thrown outwardly, and the rods 59 seek the vertical, as shown in the difference in the positions of the rods 59 in Figs. 1 and 25 3 respectively. The movement of the weights 56 and 57 outwardly pushes the link 63, and with it the sleeve 67, to the right against the flange 69, so that the latter is positioned over the outer free end of the percussion 30 hammer or lever 10, and at the same time the spring 73 is compressed. When the main shaft ceases to rotate, or the rotation drops below a certain speed, the centrifugal force acting on the weights 56 and 57 will 35 no longer be sufficient to overcome the force of the spring 73, and the latter will push the sleeve 70 to the left, thereby moving the flange out of the path of the upward movement of the outer end of the percussion 40 hammer, and if at this time the percussion hammer is under pressure, the percussion rod 12 will be driven upwardly. 45

The mode of operation of the above-described detonating mechanism will be briefly 50 recapitulated. It is assumed that the mechanism is properly attached to the vehicle which is to carry the explosive to the point where it is to be exploded. Inasmuch as the vehicle will be automatically guided and controlled, and inasmuch as in the present instance the operation of the detonating mechanism depends upon the operation of the vehicle propelling means, the main shaft 6 may conveniently be so connected with the 55 vehicle propelling means as to be set in rotation at any desired time after the vehicle is under way on its errand of destruction. The rotation of the main shaft puts the weights under centrifugal force. They accordingly swing from their normal inopera- 60

tive position, as shown in Fig. 1, to their operative position, as shown in Fig. 3. This change in position of the centrifugal weights causes the sleeve 67 to force the flange 69 over the outer end of the percussion hammer 10, at the same time compressing the spring 73. Up to this point the percussion hammer has not been cocked or put under pressure, and so if any unforeseen accident to the vehicle or to its propelling means occurs and brings the vehicle to a stop before it is beyond the friendly territory from which it is started, the explosive will not be detonated where no damage is intended. The train of gears between the main shaft 6 and the cross-shaft 32 will be so constructed and arranged as to cause the shaft 32 to rotate at any desired speed, regardless of the rate of rotation of the main shaft, so that the arm 31 will engage and force the arm 28 into engagement with the hook 35, as shown in Fig. 3, at any given point during the travel of the vehicle. The swinging of the arm 28 into engagement with the hook 35 compresses the spring 20, 70 as shown in Fig. 3, thereby cocking or putting under pressure the percussion hammer 10. This will usually take place when the vehicle is safely beyond the territory from which the vehicle starts. If the journey of the vehicle is of considerable length, the arm 31 will perform several revolutions, which, however, will not be effective on the engagement of the arm 28 with the hook 35. 75 The detonating mechanism is now in condition to cause the detonation of the explosive carried by the vehicle when the propelling means of the latter ceases to operate. It is assumed that the vehicle carries just enough fuel to take it to its destination. When the fuel is consumed, therefore, the propelling means will stop, and consequently the main shaft 6 will cease to rotate, and the weights 56 and 58 being no longer under centrifugal force, will permit the spring 73 to force the flange 69 out of engagement with the percussion hammer. Thereupon, the outer end of the latter will suddenly move upwardly under the force of the spring 20, driving the percussion rod 12 into the percussion fuse of the explosive. The explosion will 80 of course destroy the vehicle and the detonating mechanism. 85

Having thus described the invention, what is claimed is:—

1. A detonating mechanism for use in vehicles carrying explosives having, in combination, percussion means for detonating the explosive, means adapted to be connected with and to be driven by the vehicle propelling means for cocking the percussion means, and means for releasing the percussion means to cause it to detonate the explosive when the speed of the vehicle falls below a predetermined value. 130

- 4.
2. A detonating mechanism for use in vehicles carrying explosives having, in combination, percussion means for detonating the explosive, a main shaft adapted to be connected with and to be driven by the vehicle propelling means, connections between the main shaft and the percussion means constructed and arranged to cock the percussion means when the vehicle has reached a predetermined point in its flight, and means controlled by the speed of the main shaft for maintaining the percussion means inoperative when the rotation of the shaft is above a certain speed and for releasing the percussion means to detonate the explosive when the rotation of the shaft drops below a certain speed.
3. A detonating mechanism for use in vehicles carrying explosives having, in combination, a percussion hammer, a spring connected therewith, a lever to compress the spring, a shaft, connections between the shaft and the lever to actuate the latter to compress the spring, and a centrifugal device connected with the shaft to hold the percussion hammer under pressure of the spring while the shaft is rotated and to release the hammer to permit it to detonate the explosive when the shaft ceases to rotate.
4. A detonating mechanism for use in vehicles carrying explosives and provided with driving means having, in combination, means for detonating the explosive, means controlled by the driving means for cocking the detonating means, and means for maintaining the detonating means inoperative when the speed of the vehicle is above a predetermined value and for releasing the detonating means when the speed of the vehicle falls below said value.
5. A detonating mechanism for vehicles having, in combination, a normally uncocked percussion hammer, a lever for cocking the hammer, means for actuating the lever to cock the hammer when the vehicle has been in travel for a predetermined length of time, means for preventing the release of the hammer when the speed of the vehicle exceeds a predetermined value, and means for rendering the preventing means inoperative when the speed of the vehicle falls below a predetermined value.
6. A detonating mechanism for use in vehicles carrying explosives having, in combination, percussion means for detonating the explosive, and means driven by the vehicle propelling means for controlling the percussion means and for releasing the percussion means to cause it to detonate the explosive when the speed of the vehicle falls below a predetermined value.
7. A detonating mechanism for use in vehicles carrying explosives having, in combination, percussion means for detonating the explosive, a driven shaft, means actuated by said shaft for cocking the percussion means, and means controlled by the speed of said shaft for maintaining the percussion means inoperative when the rotation of the shaft is above a certain speed and for releasing the percussion means to detonate the explosive when the rotation of the shaft drops below a certain speed.
8. A detonating mechanism for vehicles having, in combination, a normally uncocked percussion hammer, means for cocking the hammer when the vehicle has been in travel for a predetermined length of time, means for preventing the release of the hammer when the speed of the vehicle exceeds a predetermined value, and means for rendering the preventing means inoperative when the speed of the vehicle falls below a predetermined value.
9. A detonating mechanism for use in vehicles carrying explosives having, in combination, means for detonating the explosive, a driven shaft, means actuated by said shaft for cocking the detonating means, and a centrifugal device actuated by the shaft arranged to release the detonating means when the rotation of the shaft drops below a certain speed.
